SYRUP VALVE

Albert R. Thompson, San Jose, Calif., assignor to
Food Machinery Corporation, San Jose, Calif.,
a corporation of Delaware

Application October 2, 1933, Serial No. 691,858

12 Claims. (Cl. 226—124)

This invention relates to fluid valve mechanisms and has to do more especially with syrup valves employed in the fruit canning industry.

In the commercial canning of fruit the procedure is first, to put into the cans the predetermined amount of solid fruit and thereafter to fill the remaining space in the cans with syrup consisting usually of a solution of sugar in water—the same practice being followed in the canning of vegetables and other products except that the fluid filler is usually brine instead of syrup.

The machines employed for filling the cans with syrup or other fluid are known as syruping machines, and these comprise elements for conveying the cans to be filled into engagement with valves (known as syruping valves) through which syrup is fed to the cans in the required quantities.

There are several prior patents pertaining to syruping valves of the general character here dealt with, and among these are United States Letters Patent Nos. 1,288,749 and 1,355,016, issued to A. R. Thompson.

Although the syruping valves of the prior art to which reference has been made are entirely practicable and, for the most part, satisfactory, it has been found that for very soft fruit such as berries, apricots and some peaches there is a tendency for the valve member which enters the can to crush the fruit and also to close up the interstices, with a resultant insufficient filling of the cans with syrup.

The object of the present invention is to devise a syruping valve which will not press down upon the fruit and which will otherwise function at least as satisfactorily as the valves heretofore in use.

The present invention is characterized in that the valve disc, instead of moving into the can upon opening of the valve, moves away from the can in the same direction of movement as the valve seat member. The novel mechanism by means of which this desirable result is accomplished can best be described in conjunction with the accompanying drawings, wherein:

Fig. 1 is a vertical sectional view through a portion of a syruping machine including the syruping valve of this invention,—the valve being shown in the closed position with a can in place and either about to be filled or having been filled;

Fig. 2 is identical with Fig. 1 except that the valve is shown in the open position wherein syrup is being admitted to the can;

Fig. 3 is a sectional view taken along the line 3—3 of Figs. 1 and 4; and

Fig. 4 is a sectional view taken along the line 4—4 of Fig. 3.

The syruping machine comprises a circular syrup tank 1 mounted to rotate about its vertical axis and around the bottom of which are arranged peripherally a considerable number of syruping valves 2 which revolve with the syrup tank in a horizontal plane. Below the syrup tank and coaxial therewith is a circular can conveyor comprising a number of can holders 3, each of which is in registration individually with one of the syruping valves. These can holders move horizontally in a circular path simultaneously with the syrup tank and valves, and a suitable mechanism (not shown) is provided for lifting the can holders together with the cans, thereby bringing the open upper ends of the cans into engagement with their respectively associated syruping valves, as shown. Each valve opens automatically, permitting a flow of syrup therethrough from tank 1 in response to a can being pressed upwardly against it; the valve automatically closing, shutting off the flow of syrup when the can is lowered. The amount of syrup fed to the can is automatically limited by the valve.

The valve structure comprises a body casting 4 which is shown threaded into the bottom plate of the syrup tank; a valve seat member 5 annular in form and slideable vertically in a recess formed in the body; a resilient valve seat ring 6; a valve disc 7 which functions also as a displacement member; a pair of bifurcated levers 8 and 9; a bridge member 10; a vent tube 11; a retracting spring 12; and a resilient packing ring 13.

The valve seat ring 6 is preferably made of resilient rubber and it serves two functions; one of these being to effect a sealed engagement between the valve and the peripheral open end of a can in contact therewith, as shown in Figs. 1 and 2, the other function being that of a valve seat coacting with the valve disc 7.

Vent tube 11 is rigidly secured in the body 4 and extends upwardly to a point above the level of the syrup in tank 1. The lower end of the vent tube serves as a guide upon which the valve disc 7 is slideable vertically into and out of engagement with the ring 6. Normally the valve disc is held down against its seat under pressure of spring 12 as illustrated in Fig. 1.

As hereinbefore stated it is a characteristic feature of this valve that the valve disc moves away from the can upon actuation instead of

into the can, and that the valve disc and valve seat member move in the same direction. This is illustrated in Figs. 1 and 2 of the drawings, in the first of which the valve is shown closed, and in the second open. It will be noted that in Fig. 2 the valve seat member 5, valve seat ring 6, and valve disc 7 have all moved upwardly, and that the valve disc has moved a greater distance than the valve seat member and ring. This unequal movement of the valve disc and its seat is effected wholly in response to upwardly directed pressure of the can against the ring 6, and is brought about by the action of a translating mechanism comprising as its principal elements the bifurcated levers 8 and 9. These levers are pivotally connected to the upper end of the valve disc member 7 through the medium of guide pins 14 and 15, which are best shown in Figs. 3 and 4. The opposite ends of levers 8 and 9 are fulcrumed at points 16 and 17 where they bear against the body casting 4. The levers 8 and 9 also rest, respectively, on cross bars 18 and 19 which form a part of the bridge member 10. The latter member is disposed within and supported by valve seat member 5 and is moveable vertically therewith.

Upon each upward movement of the valve seat member 5 the levers 8 and 9 are rotated about their respective fulcrums 16 and 17, motion being imparted thereto by the cross bars 18 and 19, respectively. It will be observed that the length of the horizontal lever arm from the fulcrum point 16 to the center of cross bar 18, and likewise from the fulcrum point 17 to the center of cross bar 19, is only about one-half the length of the horizontal lever arm from either fulcrum point to the pivoted ends of the levers. Such being the case it follows that the pivoted ends of the levers, together with the valve disc 7, will move upwardly twice the distance traversed by the cross bars 18 and 19 and the members 5 and 6. All this is clearly illustrated in Figs. 1 and 2, and will be easily understood upon a comparative inspection of those figures.

Because of the necessarily air tight seal between the can being filled and the ring 6, it is essential to provide means for venting the can, for otherwise the back pressure of entrapped air would be likely to stop prematurely the inflow of syrup. The venting must, however, be accomplished in a manner adapted to forestall an excessive back flow of syrup from the vent which would be apt to result in overfill, with its consequent waste as well as a messy dripping of syrup from the valve during the interim between the removal of a filled can and the introduction of a fresh can. These requirements are met in the present valve structure by means of the vent tube 11, the lower end of which is closed but provided with several laterally drilled openings which, when the valve is in closed position as in Fig. 1, are obstructed by the hub of the valve disc 7. During the filling operation the valve is open as shown in Fig. 2, and the lateral openings in the lower end of vent tube 11 are exposed so as to permit egress of confined air through the vent tube as the syrup flows into the can and displaces the air therein.

The speed of the syruping machine is adjusted to allow sufficient time for the cans to fill, after which the can holders and cans are automatically lowered whereupon the valve is restored to its closed position as shown in Fig. 1; and the air vent is shut off as the result of the retraction of

the valve disc and consequent closure of the vent openings.

Unless the syruping machine happens to be so timed that no more than the required amount of syrup can flow into a can, the syrup will rise in the vent tube and, if this were not automatically shut off with the closing of the valve, the syrup therein would flow back into the can upon the latter being lowered and would, of course, overflow the can.

The cans should be nearly, but not quite full after the syruping operation—partly because the cover which is afterward to be put on extends a little way into the can and partly because to fill them completely would occasion a great deal of spilling in the after handling. It will be noticed that the valve disc 7 has a concaved lower face and that in its closed position (Fig. 1) it projects a little way into the can. The concavity is to prevent or, in any event, restrict crushing of the fruit which generally is heaped up at the center as it comes to the syruping machine; and the projection of the disc into the can has for its object to force superfluous syrup back through the valve port while it is closing. The syrup content of the can will include that which occupies the space in the valve disc just below the vent tube, a part of which is above the top level of the can, and it will be apparent that the displacement effected by the valve disc should be sufficient to allow for flow-back of that syrup without overfilling. Since the valve disc, upon opening, moves away from the can instead of further into it as in prior syruping valves, the possibility of soft fruit being crushed thereby is extremely remote if not entirely eliminated; and, in addition, there being no pressure imposed upon the fruit the syrup will readily flow into the interstices, thus ensuring properly filled cans.

The function of the packing ring 13, which is preferably of soft rubber, is to provide a fluid tight joint between members 4 and 5. This ring, being circular in cross section, will roll in response to the up and down movement of member 5 and it does not present a great deal of frictional resistance to the movement of that member and will not rapidly wear out.

Referring to Figs. 3 and 4, it will be seen that the guide pins 14 and 15 rest in vertical guides which are integral with the bridge member 10. These permit the necessary vertical movement of guide pins 14 and 15 while restraining the valve disc against rotation about its axis.

The balls 20 function simply as stops to limit the downward movement of valve seat member 5 and, in turn, of the valve disc and lever arms. These balls are held in place by Scotch plugs 21.

What is claimed is:

1. A can-filling valve having a conduit therethrough for the passage of can-filling material, said valve comprising a pair of complementary valve members normally closing said conduit, one of said members being adapted to be engaged and lifted by a can-to-be-filled, the other of said members being normally positioned to project beyond said first mentioned member into the upper part of a can-to-be-filled, and means operable to raise said last mentioned member out of the can and thereby to open the valve in response to upward movement imparted to said first-mentioned member by a can-to-be-filled, both said members being positioned outside of a can-to-be-filled during filling thereof and means operable automatically to restore said members to normal position in response to a lowering movement of the can.

2. A can-filling valve having a conduit therethrough for the passage of can-filling material, said valve comprising a vertically moveable annular valve-seat member having a resilient sealing ring adapted to effect sealed engagement with the open upper end of a can-to-be-filled, and a valve-disc member normally engaging said sealing ring and co-acting therewith to close said conduit, said valve-disc member being arranged normally to project into the can, and means responsive to upward movement of said valve-seat member to impart an upward movement to said valve-disc member thereby opening the valve and withdrawing said valve-disc member from the can.

3. A can-filling valve having a vertical conduit therethrough for the passage of can-filling material, said valve comprising a vertically moveable annular valve seat member having means for effecting a sealed engagement with the open end of a can-to-be-filled, a vertically moveable valve disc normally co-acting with said valve seat member to effect a closure of said conduit, a translating mechanism disposed within said annular valve seat member, said translating mechanism comprising a plurality of levers, each of which is pivotally connected to said valve disc member and fulcrumed at points remote from said valve disc member, and means interconnecting said valve seat member with said levers at points intermediate said fulcrums and the pivoted connections of said levers to said valve disc members.

4. In a can-filling valve having a passageway to be controlled, a vertical vent tube having a lateral vent opening at its lower end, a valve disc member slideably mounted on said vent tube and normally covering said vent opening, said valve disc member being operable upon being moved upwardly from its normal position to uncover said vent opening, and a valve seat member co-acting with said valve disc member to open and close said passageway.

5. In a can-filling valve having a passageway to be controlled, a vertical vent tube having a lateral vent opening at its lower end, a valve disc member slideably mounted on said vent tube and normally covering said vent opening, a spring pressing downwardly on said valve disc member, said valve disc member being operable upon upward movement from its normal position to uncover said vent opening, a valve seat member co-acting with said valve disc member to open and close said passageway, and a translating mechanism interconnecting said valve seat member and said valve disc member, said valve disc member being moveable upwardly to open the valve in response to upward movement imparted to said valve seat member.

6. A can-filling valve comprising a fixed body adapted to be connected to a source of supply of can-filling material, said body having a passageway for filling material, an annular valve seat member slideably mounted vertically in said body, a vertical fixed vent tube supported by said body and extending coaxially therethrough, a valve seat ring carried by said valve seat member, a valve disc member slideably mounted vertically on said vent tube, a spring pressing downwardly upon and normally holding said valve disc member in engagement with said valve seat ring whereby said valve is normally held closed, said valve disc member, when closed, projecting below said valve seat ring, and a mechanism operable in response to an upward movement of

said valve seat member to lift said valve disc member out of engagement with said valve seat ring thereby opening said passageway.

7. A filling valve for can syruping machines including a valve seat member adapted to be engaged and lifted by a can to be filled without entering the can and having a passageway therethrough for communication with said can, a valve closure and displacement member cooperable with said seat member and normally positioned to close the passageway through the latter and to project beyond said valve seat member into a can presented thereto, and means actuated by upward movement of said valve seat member to elevate said valve closure and displacement member out of the can and open said passageway.

8. A filling valve for syrupers comprising a movable can seal member carried by a valve body and against which a can may be pressed, a movable valve member adapted to normally seat against said seal member and interrupt syrup flow and to project into a can while it engages said seal member, means for lifting said valve member and the projecting portions thereof above the confines of said can and to unseat said valve member upon lifting the can whereby to remove pressure from the solid contents thereof during syruping and for restoring said valve member upon lowering said can.

9. A valve comprising a hollow open ended cylindrical body portion, a tubular member reciprocable in sealed relation in said cylindrical body portion having at the end thereof a resilient ring forming a can rim engaging surface outwardly thereof and a valve seat inwardly thereof, a valve head for cooperation with said seat and mounted for movement within said body portion and reciprocable member, and means responsive to movement of said member for operating said head to effect movement thereof in the same direction as the movement of said member and to a greater extent.

10. A filling valve for can syruping machines comprising a movable valve body, a can seal carried thereby in position to preclude entry of the valve body into the confines of a can presented into sealing engagement with said can seal, said valve body and can seal having a liquid conducting passageway therethrough for communication with said can, a valve seat within said passageway, a movable valve normally seated on said valve seat to close said passageway and to project below said seal into the confines of a can presented thereto, and valve actuating means operable in response to upward movement of said valve body upon elevation of the can against the seal to lift said valve from the valve seat to open said passageway and to simultaneously withdraw the valve out of the confines of the can to prevent excessive pressure by the valve on the contents of the can during the filling operation, said valve actuating means being operable upon descent of the valve body to lower said valve whereby it reenters the can to displace a portion of the liquid therefrom and thereafter closes said passageway.

11. In a fruit syruping device, a normally closed valve structure comprising a sealing part engageable by a can rim while remaining without the can and having a valve seat therein, and a valve closure seated on said valve seat and normally projecting beyond the sealing part so as to enter such can, and means responsive to moving engagement of such can rim and sealing

part for moving the valve closure out of the can.

12. A filling valve for can syruping machines comprising a movable valve body having a liquid conducting passageway therethrough and provided with a can seal for sealing engagement with the open end of a can presented thereto for filling, a valve seat within said passageway, a movable valve normally seated on said valve seat to close said passageway and to project below said seal into the confines of a can presented thereto, means providing an air vent passage having an opening at its lower end for communication with a can during the filling operation, valve actuating means operable in response to upward movement of said valve body upon elevation of the can against the seal to lift said

valve from the valve seat whereby to open said liquid conducting passageway and to simultaneously withdraw the valve out of the confines of the can to prevent excessive pressure by the valve on the contents of the can during the filling operation, said valve actuating means being operable upon descent of the valve body to lower said valve whereby it reenters the can to displace a portion of the liquid therefrom and thereafter closes said liquid conducting passageway, and means associated with said valve for covering said air vent opening when the valve is seated and operable to uncover said vent opening when the valve is unseated.
